UNITED STATES PATENT OFFICE.

SOLOMON TOWNSEND HOLLY, OF LOS ANGELES, CALIFORNIA, ASSIGNOR OF ONE-FOURTH TO CARRIE C. HOLLY, ONE-FOURTH TO LUTHER M. MARSTON, AND ONE-FOURTH TO ANNIE M. MARSTON, ALL OF LOS ANGELES, CALIFORNIA.

REGULATOR FOR TURBINES.

942,828.

Specification of Letters Patent.

Patented Dec. 7, 1909.

Application filed November 4, 1907. Serial No. 490,717.

To all whom it may concern:

Be it known that I, SOLOMON TOWNSEND HOLLY, a citizen of the United States, residing at Los Angeles, in the county of Los Angeles and State of California, have invented new and useful Improvements in Regulators for Turbines, of which the following is a specification.

The invention relates to regulators for turbines, and has particular reference to regulators for that class of turbines of the type disclosed and claimed in my Patent 858,599, issued July 2, 1907, but it is also adapted for an improved form of turbine, which comprises a rotor provided with peripheral pockets or buckets, divided and separated by a central diaphragm or disk, which divides the inflowing stream of steam under pressure, into two distinct streams, each impinging against the buckets or pockets on opposite sides of said central diaphragm or disk. The improved form of turbine does, however, form no part of the present invention, but will be made the subject of another patent, the present illustration thereof, having been made merely to make a more lucid disclosure of the regulator to be hereinafter described.

One of the main objects of this invention, is to provide a regulating means for varyingly controlling the series of tapering steam discharging nozzles at the point of smallest area, in order to obtain the greatest density and pressure at a point as near as possible to the terminus of the nozzles, and to the apex of each bucket of the turbine.

Another object of this invention is to provide an easily controllable regulator, in which the area of discharge of the motive fluid is capable of being varied, whether issuing from the steam reservoir at the highest or smallest pressure, and in a maximum or minimum quantity.

With these and other objects in view, my invention consists in such features, details of construction and combination of parts, as will be described in connection with the accompanying drawings, and then be more particularly pointed out in the claims.

In the drawings Figure 1 is a longitudinal section showing the improvement partly in fragment. Fig. 2 is a side elevation of the ring valve controlling levers, the same being shown detached. Fig. 3 is an end elevation

of the same. Fig. 4 is a fragmentary vertical section on lines X—X of Fig. 1, shown partly broken. Fig. 5 is a longitudinal vertical section, showing an external regulating mechanism, part of the turbine proper being shown in fragment. Fig. 6 is a side elevation of the turbine, showing the regulating mechanism assembled. Figs. 7, 8, 9 and 10 are fragmentary details of the rack and pinion mechanism for controlling the valves within the case.

1 designates the case.

2 is the rotor provided with a duplicate row of peripheral buckets or pockets 3 and 4.

5 is an annular diaphragm or disk centrally dividing the buckets 3 and 4 and fastened to the rotor by bolts or screws or in any other manner. The rotor proper is bolted to a hub, 6, which is keyed to a shaft, 7, journaled in case 1.

8 is the main frame of the case 1, which together with the annular ring 9 forms the steam chest or reservoir.

10 is an annular web or disk forming a division plate between the nozzles 11.

12 designates two annular series of adjustable members provided on opposite sides of the web 10, and pivotally screwed thereto by the bolts 13, which extend transversely through the case.

14 designates a plurality of valve rests, riveted to the center web 10, against one side of which the rear of the valve members 12 bear, and the opposite side of which forms a portion of the nozzle for the in-flowing steam, so that in conjunction with the valve members 12, a series of tapering steam nozzles are obtained, which by reason of their movement on their pivotal axes are intended to vary at different times the quantity of the impelling fluid, while at the same time preserving the greatest density at the point where the steam enters the buckets or pockets of the rotatable member.

15 designates two annular rings, one on each side of the diaphragm 10 and loosely fitted within the frame 8 of the case. They are provided with openings 16, through which steam is admitted and also with recesses 17 to receive the projecting ends 18 of the valve members 12 in which recesses these ends of the valve members are normally housed; said rings 15 are also pro-

vided with recesses 19 on opposite sides of each ring, said recesses being arranged to accommodate the projecting tangs 20 of the actuating levers 21 and 22, one of which is keyed or firmly secured in any manner to the shaft 23, which extends through and is journaled in the case.

As will be seen from Figs. 2 and 3, the lever 22 is keyed to the shaft. It comprises a disk member, having a tang 20 aforementioned. The disk portion of said lever 22 is provided with a small web or projection 24 and with openings 25. The lever 21 is also mounted on shaft 23, but loosely and adjustably relatively to the lever 22 and for this reason the disk portion of the lever 21 is provided with slightly curved slots 26 and with angularly disposed lugs 27, provided with screw threaded openings arranged to receive the set screws 28 as seen in Fig. 4. The said lever 21 is fitted on to shaft 23, so that the lugs 27 stand on opposite sides of the projecting web or lug 24. The bolts 29 are then extended through the walls 26 and into an opening 25 provided therefor, whereupon, when the correct position of the lever 21 has been ascertained, the bolts are screwed home to tightly hold the same against movement on the shaft 23 and relatively to the other lever 22. In other words, the two levers are secured together to move as one part, after the positive adjustment of the lever 21, so that although no variation results in the amount of travel of the ring, for controlling the valve members, more steam is nevertheless admitted to one series of buckets than to the other series. Various advantages are accomplished by thus providing for the adjustability of the two valve controlling levers, the most important of which may be stated, to reside in the compensation or balancing of the rotatable member, when for any reason the turbine is made to assume a position which is at an incline to the horizontal. In this manner, the end thrust is regulated and the wheel held in steady balance.

30 is a plate removably bolted to the outside ring 9 which forms part of the steam reservoir, and which is provided for the purpose of effecting the adjustment of the lever 21.

On the shaft 7 is a worm 31 with which a similar worm gear 32 meshes. This worm gear 32 is mounted on the end of a shaft 33, which is held in place by the bracket 34 secured to the case 1, shaft 33 being journaled in the framework 35 for the external regulating mechanism. On the opposite end of the said shaft 33 is a bevel wheel 36 meshing with a bevel wheel 37 keyed to a shaft 38 which is journaled in the framework 35. On the end of the shaft 38 is another bevel wheel 39 which meshes with the bevel wheel 40 keyed on to the end of a vertical shaft 41.

42 is a sleeve provided with two bevel gears 43 and 44, which are made integral with the sleeve and spaced apart a predetermined distance for purposes to be more fully hereinafter specified. This sleeve 42 is splined on to the shaft 41, and is capable of a vertically sliding movement thereon. The upper portion of the sleeve is provided with an annular groove 45 to receive the short levers 46, provided on the ends of the two arms 47, which carry the revolving regulating balls 48.

49 is a yoke keyed fast to the shaft 41 and the arms 47 are pivotally secured thereto.

50 designates a helical spring, one end of which is secured to the lug 49' on one of the arms 47 and the other end of which is provided with a loop adapted to be engaged by an eye L on one end of the bar 52. Said bar extends through an orifice in the lug 51, and at its other end is provided with a jam nut and a lock nut for the purpose of adjustably mounting the bar in the lug, to regulate the degree of tension of spring 50 which the centrifugal action of the revolving balls must overcome before moving outward. It is obvious that in this manner but a limited movement of the regulating balls is permissible, a circumstance which is necessary for the very limited movement of the regulating valve ring under various degrees of loads.

As shown by the drawings, the revolving weight shaft 41 is supported by the spider frame 54. The globular portion 55 consists of upper hemisphere A and lower hemisphere B, said upper hemisphere carrying shaft 41 and said lower hemisphere being supported by frame 54. Said hemispheres are provided with oppositely disposed circular grooves on their flat sides to form raceways for receiving a plurality of anti-friction balls 56. When the upper half of the globe is properly secured to the weight shaft 41, it holds the weighted means securely and allows it to revolve with perfect freedom.

57 is a spider bolted to the frame 35 and made in two pieces to loosely fit the sleeve 42. It is provided with a stud 58, on which is loosely mounted a bevel wheel 59, which is held in place by the cap 60 and screw 61. This bevel wheel 59 occupies the space between the bevel wheels 43 and 44 provided on the sleeve 42. None of the aforementioned wheels are provided with gears, but depend upon friction to impart movement to the bevel wheel 59. When increase of the speed of the turbine causes the regulating balls to spread, they raise the sleeve which is keyed on to the shaft and bring the bevel surface of the lower bevel wheel 43 into frictional engagement with the bevel surface of the bevel wheel 59. On the other hand, when the speed decreases, the balls by reason

of the springs, are drawn inwardly toward the center of the spider, causing the sleeve 42 to travel downwardly, pressing the face of the bevel wheel 44 into engagement with the bevel face of the bevel wheel 59, to rotate said wheel 59 in the reverse direction to the rotation imparted by the bevel wheel 43.

62 is a shaft provided with a ball 63, fitting in a socket 64, provided in bevel wheel 59.

65 is a gear wheel firmly secured to the shaft 62 and connected with the shaft 66 by a gimbal or universal joint 67. The gear wheel 65 meshes continually with the gear wheel 68 stationarily mounted on the frame 35; the said gear wheel being provided with a greater number of teeth than the gear wheel 65, in order to cause each gyroscopic movement of arms 62 and gear 65 to produce a partial rotation of shaft 66 and pinion 69, the extent of such rotation being determined by the difference between the number of teeth in gears 65 and 68. The gyroscopic gear avoids the loss of motion liable to result from compounding several gears. The fixed gear is provided with more teeth than the gyroscopic gear in order to have a differentiation, which depends entirely upon the amount of "gearing back". The amount of rotation imparted to the pinion by each gyration of gear 65 is calculated to be equivalent to the circumferential distance covered by the excess number of teeth in gear 68 over the number of teeth in gear 65. The power transmitted to the pinion is thus greatly compounded. The gyroscopic means includes gear 65 and arm 62, said arm having an end 63 eccentrically connected with bevel gear 59 and having its other end mounted in line with the axis of gear 59.

That portion of the regulating device located within the turbine case, which includes the series of expandable nozzles, is of such a nature that it requires but a very limited movement of the annular actuating ring for simultaneously expanding and contracting all of the nozzles or steam passages to admit steam to the turbine.

If for any reason of neglect or other cause, the steam pressure should become so low as to fail to maintain the desired speed when the expandable nozzles are opened to their limit, an alarm is sounded by a bell 78 and a vibrating tooth 75 at the end of the rack 70. Said tooth is so hinged that when it is moved under the center of the driving pinion 69, the sliding support 76 is pushed from beneath it by being brought against a stud or pin 77 located on the regulator frame. The further action of the pinion in that direction will push the hinged tooth down and slip the gear 69, allowing the same to revolve without further movement of the rack. The vibrating of the tooth, vibrates a ball 65 or hammer, and gives a signal on a bell 78

suitably located, as shown. On the reverse movement of the pinion, the spring 79 beneath the vibrating tooth, holds it up to its normal position, and the reverse action of the pinion has no tendency to depress it. In moving the rack in the direction to decrease the discharging capacity of the nozzles, the effect would be to entirely close the nozzles and therefore stop the engine, so that no guard or safety tooth is required at that end of the rack. In practice, it is not deemed advisable to use the adjustable nozzles to start and shut down the engine, but preferably the main admission valve. This is, however, within the discretion of the engineer.

As shown by the drawings, the valve rests 14 are approximately triangular in their general cross section outline and are ranged around the turbine in an annular series, being spaced circumferentially apart to leave steam inlets between adjacent valve rests. Each valve rest is provided with a curved rear portion adapted to receive a correspondingly curved heel with which each valve member 12 is provided. Said valve members 12 are provided with two arms, one of which projects rearwardly and has a slightly curved inner side to form in connection with the next rearward valve rest, a forwardly directed steam inlet; the other arm of each valve member 12 extends radially outward from its heel and is operatively engaged by the regulating ring 15. The curved heels of the valve members at all times form a close fit against the curved rear portions of the valve rests so that the steam cannot escape past the heels.

The ring for operating the various valves, or valve members, as they have been termed, may be controlled and operated by the levers 73, which are inter-connected by the bar 71, in which case the cam lever 74 operates to throw the rack 70 out of mesh with the pinion 69. It is evident that any movement of the ring produces a movement of the valve members on their pivotal axes, which movement regulates the amount of steam that is to be admitted to the rotor of the turbine. The ring itself is held freely within the case and upon the ends of the valve members.

What I claim is:

1. A regulator for turbines comprising an annular series of pivotal valve members forming nozzles, circumferentially moving means to control said valve members, gyroscopic means to regulate said controlling means, a governor, and gearing operating between said governor and said gyroscopic means, said gyroscopic means being provided with an arm for gyroscopic movement, one end of said arm being eccentrically connected with a gear of said gearing and the other end of said arm being mounted axially in line with said gear.

2. A regulator for turbines comprising annular series of pivotal valve members forming nozzles, internal means engaging said valve members for moving the same, means to move one series of valve members a greater distance than another series, and external means for operating said means.

3. A regulator for turbines comprising two annular series of pivotal valve members forming nozzles, means for moving said valve members to control the size of the nozzles, and means for governing said moving means to give a greater movement to one series of valve members than to the other.

4. A regulator for turbines, comprising annular series of pivotal valve members, forming expansive fluid nozzles, circumferentially movable rings, carried by said valve members, for simultaneously actuating all of said members, and means for giving a greater circumferential movement to one of said rings than to the other.

5. A regulator for turbines, comprising annular series of pivotal valve members, forming expansive fluid nozzles, circumferentially movable rings carried by said members, for actuating all of said members, means for actuating said rings, and means for governing said means, to give a greater circumferential movement to one of said rings than to the other, for controlling the size of the nozzle.

6. A regulator, comprising a diaphragm, located in proximity to the rotatable member of a turbine; a plurality of regulable nozzles on opposite sides of said diaphragm, freely movable rings, for regulating the size of the nozzles, means for circumferentially moving said rings, to control said nozzles, and means for adjusting said means, to vary the distance of travel of one of said rings, relatively to the other.

7. A regulator for turbines, comprising the case and rotor, journaled in said case, a diaphragm in proximity to the rotor, a plurality of fixed and movable members on said diaphragm mutually interacting to form nozzles of varying dimensions, means for limiting the movement of said movable members, rings normally engaging said members, for operating said movable members, means for controlling said rings, to gage the movement circumferentially, of the rings, relatively to each other, and regulating means, externally of the case, for controlling said means.

8. A regulator for turbines comprising pivotal valve members, and rings for actuating said valve members, in combination with means for actuating said rings comprising a rack, a pinion in engagement with said rack, a speed governor, gears 65 and 68 for producing a differential speed between said pinion and governor, and means connected to the shaft of the turbine-rotor for

imparting movement to said actuating means.

9. The combination with a case, a shaft journaled in said case, and a rotor mounted on said shaft, of a ring in said case, provided with a plurality of steam passages or nozzles, a ring extending around the turbine for regulating the size of said nozzles, means for rotating said regulating ring, a shaft for operating said means, a stationary gear surrounding said shaft and having teeth facing toward one end of said shaft, a gyratory gear having a different number of teeth from the teeth of said stationary gear, an arm for gyrating said gyratory gear while maintaining it in mesh with said stationary gear, said gyratory gear being fixed to said arm and said arm being attached by a universal joint to said shaft, a governor, and means operatively connecting said governor with said arm to gyrate the same.

10. A regulator for turbines comprising an annular series of pivoted valve members, a series of valve rests interposed between said valve members, there being a chamber extending radially outward from said valve members and valve rests forming an annular steam chest, each valve rest coöperating with a valve member on one side thereof to form a nozzle and being pivoted adjacent to and having a close fit with the valve member on the opposite side thereof, and means within said steam chest to operate said valve members.

11. A turbine having an annular series of pivoted valve members, a series of valve rests triangular in general outline between said valve members, an annular steam chest surrounding said valve members and valve rests, each valve rest having a nozzle on one side thereof and one of said valve members in contact with the other side thereof, a ring in said steam chest operatively connected with said valve members to regulate the discharge of said nozzles, and means for moving said ring.

12. A turbine having an annular series of valve rests spaced circumferentially apart to form inwardly directed steam inlets therebetween, said valve rests having curved rear portions, a series of pivoted valve members provided with curved heels engaging the curved portions of said valve rests, said valve members having a rearwardly projecting arm adapted to coöperate with the next rearward valve rest to form a nozzle, and an operating arm extending radially outward from said heel, an annular steam chest surrounding said valve rests and valve members, a ring in said steam chest operatively engaging said radial arms of said valve members and means for moving said ring circumferentially to control the size of said inlets.

13. A regulator for turbines comprising

inlet means, means for controlling the size of said inlet means, said controlling means comprising a toothed rack, a governor, means operated by the turbine for rotating 5 said governor, a pinion controlled by said governor for moving said rack, means at one end of said rack to lower the same out of engagement with said pinion, and means at

that end of said rack to manually operate the same when in the lowered position. 10

In testimony whereof I affix my signature, in presence of two subscribing witnesses.
